(57) **CLAIM**

The ornamental design for a drywall cutout tool, as shown and described.

DESCRIPTION

FIG. 1 is a front perspective view taken from the left side of a drywall cutout tool showing our new design.

FIG. 2 is a left side elevational view thereof.

FIG. 3 is a right side elevational view thereof.

FIG. 4 is a top plan view thereof.

FIG. 5 is a bottom plan view thereof.

FIG. 6 is a rear elevational view thereof; and,

FIG. 7 is a front elevational view thereof.

The broken line showing in FIG. 5 is for illustrative purposes only and forms no part of the claimed design.
